UNITED STATES PATENT OFFICE.

JOHN FRANKLIN EWELL, OF CHICAGO, ILLINOIS.

VALVE FOR TANK-CARS.

1,150,586.

Specification of Letters Patent. Patented Aug. 17, 1915.

Application filed March 16, 1914. Serial No. 825,113.

To all whom it may concern:

Be it known that I, JOHN FRANKLIN EWELL, a citizen of the United States, and a resident of the city of Chicago, in the county of Cook and State of Illinois, have invented a certain new and useful Improvement in Valves for Tank-Cars; and I do hereby declare that the following description of my said invention, taken in connection with the accompanying sheet of drawings, forms a full, clear, and exact specification, which will enable others skilled in the art to which it appertains to make and use the same.

15 This invention relates to valves in general and to valves for tank cars in particular and has for its object the provision of an operating mechanism for such a valve which will maintain the same in its open or closed 20 positions.

Tank car valves as generally made have a valve seating in the car bottom and a valve adapted to rest thereon. The valve proper has an upstanding stem guided in a yoke 25 formed integral with the valve seating. In some cases this yoke is internally tapped and the valve stem possessed of a mating external thread, whereby by rotation of the stem the said valve is seated or unseated.

30 The valve stem in all cases arises into the dome of the car within which the said stem terminates in a hand lever, hand wheel, or other means for hand rotation of the stem.

These rotation means are variously supplied 35 with lock nuts, padlocks, and similar devices to maintain the valve stem in a set position. But the vibration of the car in travel, the various distortions created, and the constant stresses and reversals thereof 40 which are set up, all tend to a loosening of the valve stem from its lock and a constantly increasing oscillation thereof until the valve has sufficiently receded from its seat to cause it to leak.

45 The present invention is designed to cause the valve to remain seated upon its seat, irrespective of the constant vibration, distortion, and stress reversals continuously taking place in a structure of the class described while the same is in motion and loaded to its full capacity.

With the above and other objects in view, this invention consists in the construction, combination and arrangement of parts, all 50 as hereinafter more fully described, claimed.

and illustrated in the accompanying drawings.

In the drawings already referred to which serve to illustrate my said invention, Figure 1 is a central vertical section of a tank car illustrating the present invention embodied therein. Fig. 2 is a horizontal section taken along line 2—2 of Fig. 1, and is a plan view of the valve operating mechanism. Fig. 3 is an enlarged side elevation 65 of the valve operating mechanism illustrating, in dotted lines, the position of the elements thereof when the valve is closed.

Reference being had more particularly to the drawings, 10 designates a tank car of the usual construction having the diametrically opposed inlet and discharge opening 11 and 12, respectively, the inlet opening 11 being surrounded by the customary dome 13. A valve stem 14 extends from one side 70 of the dome 13 to the discharge opening 12 where it passes through a guide 15 which spans said discharge opening. This valve stem is adjustable as to its length by means of a turnbuckle 16 medial of its length or 75 any other suitable or adaptable device. The lower end of the stem 14 has a valve 22 secured thereto so that the same is seated in the discharge opening 12 or removed therefrom by the reciprocation of the said stem. 80

In order to reciprocate the stem 14 and to maintain it in position, a support 17 is interposed between the walls of the dome, through which the upper end of the stem 14 freely and loosely projects. Secured to 85 the support 17 upon each side of the stem 14 is an upstanding spring tempered blade or bar 18, which bars are susceptible of deflection at their upper ends in either direction upon application of forces in the proper direction, and to return to their 90 normal positions upon the removal of such forces; the normal, unstressed position of said blades being slightly toward each other at their upper ends. A pair of centrally pivoted together toggle links 19 (the central pivot of which also forms the support for the stem 14, Figs. 1 and 3) are pivoted at their free ends to the upper ends of the 95 spring tempered blades 18, and the said links are still at an upwardly pointing obtuse angle to each other after the blades 18 have been deflected slightly beyond the perpendicular, away from each other. In this 100 position of the parts, the valve is still in 110

open position, the weight of the valve and stem creating a stored force or energy in the blades 18, which is expressed in their deflection. Fixed to one of the links 19 5 there is a hand lever 20, its free end thereof contacting with the shell of the tank 10 to arrest any possible upward movement of the stem 14 and toggle links 19 under the influence of the stored energy in the spring 10 blades 18.

When it is desired to close the valve 22 the lever 20 is lifted in order to assist the toggle links in enforcing a sufficient deflection in the blades 18 to allow said toggle to 15 pass the "critical" or "lock" point, whereupon the total stored energy in the deflected blades expresses itself in a sudden downward force upon stem 14, through the links 19, and in this downward force the blades 20 are assisted by the weight of the stem and valve, thereby firmly seating said valve upon its seat and maintaining it there. When the valve is seated, there is still an amplitude of stored energy in the blades 18 to maintain 25 said valve upon said seat under all operating conditions. It will thus be seen that no amount of vibration or distortion of the tank car or body itself will affect this downward force of the blades as long as the shell 30 of the tank itself is not wrecked and the relationship of the parts of the valve mechanism entirely destroyed.

It will be noted that the toggle links and spring bars not only act to maintain the 35 valve in its seat with a spring tension but also to hold the valve stem and valve in an elevated unseated or open position as shown in Figs. 1 and 3.

The advantage of this construction is that 40 it is double acting, serving to hold the valve and its stem in either of its two positions with sufficient spring tension to prevent any unintentional involuntary movement from one position to another through vibration or 45 other cause.

The spring bars 18 as shown are constructed of straight flat thin strips of suitable metal. The flat springs 18, are sufficiently stiff to support the bar 20 with its

outer portion elevated when the parts are 50 in the dotted line position shown in Fig. 3.

While herein I have disclosed the preferred method of practising my invention, I desire it understood that I may make such changes and alterations therein as might 55 suggest themselves to the skilled mechanic or permitted under the doctrine of equivalents.

Having thus fully disclosed my invention I claim as new and desire to secure to myself 60 by Letters Patent of the United States:

1. In combination, a tank body and a valve seat therein, of a valve adapted to close against said seat, a stem for said valve, a pair of toggle links pivoted at their inner 65 ends to the valve stem and spring bars pivoted at their upper ends to the outer ends of the toggle links and rigidly fastened at their lower ends to the tank body.

2. In combination, a tank body and a 70 valve seat therein, of a valve adapted to close against said seat, a stem for said valve, a pair of toggle links pivoted at their inner ends to the valve stem and spring bars pivoted at their upper ends to the outer ends 75 of the toggle links and rigidly fastened at their lower ends to the tank body; said spring bars being straight, flat and thin.

3. In combination, a tank body and a valve seat therein, of a valve adapted to 80 close against said seat, a stem for said valve, a pair of toggle links pivoted at their inner ends to the valve stem, spring bars pivoted at their upper ends to the outer ends of the toggle links and rigidly fastened at their 85 lower ends to the tank body, and a comparatively long lever bar attached at one end to one of the toggle links and adapted to contact with its outer end against the tank body to limit the opening movement of the valve 90 stem and valve.

In testimony whereof I have hereunto set my hand in the presence of two subscribing witnesses.

JOHN FRANKLIN EWELL.

In the presence of—

WILLIAM O. STARK,
C. S. STARK.
